(57) **CLAIM**

The ornamental design for a drip edge on galley work surface, as shown and described.

DESCRIPTION

FIG. 1 is a perspective view of the drip edge on galley work surface showing our new design;

FIG. 2 is a front view of the drip edge on galley work surface of FIG. 1;

FIG. 3 is a back view of the drip edge on galley work surface of FIG. 1;

FIG. 4 is a left view of the drip edge on galley work surface of FIG. 1;

FIG. 5 is a right view of the drip edge on galley work surface of FIG. 1;

FIG. 6 is a top view of the drip edge on galley work surface of FIG. 1;

FIG. 7 is a bottom view of the drip edge on galley work surface of FIG. 1;

FIG. 8 is a perspective view of the drip edge on galley work surface of FIG. 1 in a stowed configuration;

FIG. 9 is a front view of the drip edge on galley work surface of FIG. 1 in the stowed configuration;

FIG. 10 is a left view of the drip edge on galley work surface of FIG. 1 in the stowed configuration;

FIG. 11 is a right view of the drip edge on galley work surface of FIG. 1 in the stowed configuration;

FIG. 12 is a perspective view of the drip edge on galley work surface of FIG. 1 in a deployed configuration;

FIG. 13 is a front view of the drip edge on galley work surface of FIG. 1 in the deployed configuration;

FIG. 14 is a left view of the drip edge on galley work surface of FIG. 1 in the deployed configuration; and,

FIG. 15 is a right view of the drip edge on galley work surface of FIG. 1 in the deployed configuration.

In FIGS. 1-15, broken lines indicate environmental structure that forms no part of the claimed design.
